UNITED STATES PATENT OFFICE.

H. R. CRAMPTON, OF LOCKPORT, NEW YORK.

BED-BOTTOM SPRING.

Specification of Letters Patent No. 30,049, dated September 18, 1860.

To all whom it may concern:

Be it known that I, H. R. CRAMPTON, of Lockport, in the county of Niagara and State of New York, have invented certain 5 new and useful Improvements in Bed-Springs; and I do hereby declare that the following is a full, clear, and exact description of the same, reference being had to the accompanying drawings and to the letters of 10 reference marked thereon.

The nature of my invention consists in constructing and arranging the several parts of this bed substantially in the manner hereinafter specified.

15 In the annexed drawings Figure 1 represents an end view. Fig. 2 represents a plan view. Fig. 3 is a side elevation.

In the figures *n, n*, seen in Fig. 1, and in dotted lines, Fig. 3, represent a series of 20 slats, which form as it were the foundation of the bed, said slats being placed a short distance apart, and crosswise of the bed are secured together by means of the lower binders *s, s*. The springs *m, m*, (which are coiled 25 wire) rest upon these slats, the ends of the springs being secured in them, to keep them in proper position.

a, a, a, represent a series of slats which 30 form the top of the bed. Said slats are secured and connected together by means of the binders *c, c*, which run across them as represented in Fig. 2. The slats *a, a*, are constructed of wood and are made to spring to accommodate themselves to pressure 35 placed upon them. *d, d*, represent straps which connect the slats *n, n*, to the top spring slats *a, a, a*, at their ends.

The springs *m, m*, resting upon slats *n, n*, press against the bottoms of slats *a, a*, and 40 keep the straps *d, d*, tightly stretched when the bed is not in use.

This bed is divided in two parts as shown in Figs. 2, and 3, said parts being connected together by means of hinges *e, e*, which are 45 secured to the binders *c, c*.

Head rests *D, E*, (being of different heights) are secured under the head part of the bed in order to raise or lower that portion of said bed as circumstances may require. The binders *c, c*, are made elastic, 50 as seen in Fig. 3.

By this arrangement, it will be observed that when pressure is placed upon the bed—for instance, at *x*—the binder *c*, from *x'* to *x''*, will assist in supporting it at that point 55 being themselves supported by the slats *a, a*, over them, and by the springs under said slats. So if pressure is applied at *x''*, the binders *c*, from *x'* to *x*, and from *z*, to *z'*, will assist in supporting it, being themselves 60 supported by the slats and springs as represented.

c', represents that portion of the binder upon the head of the bed, and it will be clearly seen that as the two parts are hinged 65 together the same rule just spoken of will apply. When pressure is applied to the head piece or near the joint one portion of the binder will support the other. Thus the slats and binders are secured together in 70 such a manner that they support each other, being themselves sustained by the springs.

I do not claim the parts of this bed separately and distinctly considered; but

Having thus fully described my invention 75 what I claim as new and desire to secure by Letters Patent is—

The spring slats *a, a*, the binders *c, c*, and *s, s*, the end straps *d, d*, the springs *m, m*, and the bottom slats *n, n*, the binders *c, c*, 80 being hinged as represented and the several parts constructed and arranged substantially in the manner and for the purpose herein specified.

H. R. CRAMPTON.
